CERTAIN 2-AMINO-4-ARYL-5-N,N-DISUBSTITUTED AMINO-LOWER ALKYL-THIAZOLE COMPOUNDS

Charles Ferdinand Huebner, Chatham, N.J., assignor to Ciba Corporation, New York, N.Y., a corporation of Delaware

No Drawing. Filed Sept. 29, 1964, Ser. No. 400,197
11 Claims. (Cl. 260—306.8)

This application is a continuation-in-part application of my copending application 166,928, filed January 17, 1962, and now abandoned.

The present invention concerns 2-amino-thiazoles. More particularly, it relates to 2-amino-4-carbocyclic aryl-5-N,N-di-substituted amino-lower alkyl-thiazoles, in which lower alkyl separates N,N-disubstituted amino from the 5-position of the thiazole ring by at least two carbon atoms, or salts thereof, as well as quaternary ammonium compounds thereof.

The amino group attached to the 2-position of the thiazole nucleus is above all an N-unsubstituted primary amino group. It may also represent a secondary, or N-monosubstituted amino group, such as N-aliphatic substituted amino, for example, N-lower alkyl-amino, e.g. N-methyl-amino, N-ethyl-amino, N-propyl-amino, N-isopropyl-amino, N-butyl-amino and the like, N-cycloalkyl-amino, in which cycloalkyl has from three to eight, preferably from five to seven, ring carbon atoms, e.g. N-cyclopropyl-amino, N-cyclopentyl-amino, N-cyclohexyl-amino and the like, N-cycloalkyl-lower alkyl-amino, in which cycloalkyl has the above given meaning, e.g. N-cyclopentylmethyl-amino, N-(2-cyclohexylethyl)-amino and the like, N-carbocyclic aryl-amino, particularly N-monocyclic carbocyclic aryl-amino, such as N-phenyl-amino, or N-(substituted phenyl)-amino, in which one or more than one of the same or of different substituents may be attached to any position available for substitution, for example, N-(lower alkyl-phenyl)-amino, in which lower alkyl is methyl, ethyl, N-propyl, isopropyl, N-butyl and the like, N-(lower alkoxy-phenyl)-amino, in which lower alkoxy is methoxy, and the like, N-(halogeno-phenyl)-amino, in which halogeno is chloro, and the like, N-(nitro-phenyl)-amino, N-(amino-phenyl)-amino, N-(N,N-di-lower alkyl-amino-phenyl)-amino, in which N,N-di-lower alkyl-amino is N,N-dimethyl-amino, N,N-diethylamino and the like, N-(trifluoromethyl-phenyl)-amino, or any other N-carbocyclic aryl-amino group, N-monocyclic arylaliphatic substituted amino, such as N-monocyclic carbocyclic aryl-lower alkyl-amino, for example, N-phenyl-lower alkyl-amino, e.g. N-benzylamino, N-(2-phenylethyl)-amino and the like, or N-(substituted phenyl)-lower alkyl-amino, for example, N-(lower alkyl-phenyl)-lower alkyl-amino, N-(lower alkoxy-phenyl)-lower alkyl-amino, N-(halogeno-phenyl)-lower alkyl-amino, N-(nitro-phenyl)-lower alkyl-amino, N-(amino-phenyl)-lower alkyl-amino, N-(N,N-di-lower alkyl-amino-phenyl)-lower alkyl-amino, N-(trifluoromethyl-phenyl)-lower alkyl-amino and the like, as well as a tertiary or N,N-disubstituted amino group, such as one of those described below.

The carbocyclic aryl group attached to the 4-position of the thiazole nucleus is above all a monocyclic carbocyclic aryl group, such as phenyl or substituted phenyl, which may have one or more than one of the same or different substituents attached to any of the positions available for substitution; substituents are, for example, lower alkyl, e.g. methyl, ethyl, n-propyl, isopropyl and the like, trifluoromethyl, lower alkoxy, e.g. methoxy, ethoxy, n-propoxy, isopropoxy, n-butoxy and the like, lower alkenyloxy, e.g. vinyloxy, allyloxy and the like, lower

alkylenedioxy, e.g. methylenedioxy and the like, halogeno, e.g. fluoro, chloro, bromo and the like, lower alkyl-mercapto, e.g. methylmercapto, ethylmercapto and the like, nitro, amino, such as N,N-di-lower alkyl-amino, e.g. N,N-dimethylamino, N,N-diethylamino and the like. Substituted phenyl groups are more especially (lower alkyl-phenyl, (trifluoromethyl)-phenyl, (lower alkoxy)-phenyl, (lower alkenyloxy)-phenyl (lower alkylenedioxy)-phenyl, (halogeno)-phenyl, (lower alkyl-mercapto)-phenyl, (nitro)-phenyl, (amino)-phenyl, particularly (N,N-di-lower alkyl-amino)-phenyl and the like, or any other suitably substituted phenyl group. The carbocyclic aryl radical attached to the 4-position may also be a bicyclic carbocyclic aryl radical, such as naphthyl, 1-naphthyl or 2-naphthyl, or substituted naphthyl; one or more than one of the same or of different substituents may be attached to any of the positions available for substitution, and substituted naphthyl groups are represented, for example, by (lower alkyl)-naphthyl, (trifluoromethyl)-naphthyl, (lower alkoxy)-naphthyl, (lower alkenyloxy)-naphthyl, (lower alkylenedioxy)-naphthyl, (halogeno)-naphthyl, (lower alkyl mercapto)-naphthyl, (amino)-naphthyl, (nitro)-naphthyl, particularly (N,N-di-lower alkyl-amino)-naphthyl and the like.

The N,N-disubstituted amino portion of the N,N-disubstituted amino-lower alkyl group attached to the 5-position is primarily N,N-disubstituted amino, in which the substituents are above all lower alkyl, as well as lower alkenyl, cycloalkyl, cycloalkyl-lower alkyl, monocyclic carbocyclic aryl, particularly phenyl, monocyclic carbocyclic aryl-lower alkyl, particularly phenyl-lower alkyl and the like. N,N-disubstituted amino groups are therefore, N,N-di-lower alkyl-amino, e.g. N,N-dimethylamino, N-ethyl-N-methyl-amino, N,N-diethylamino, N,N-di-n-propylamino, N,N-di-isopropyl-amino and the like, as well as N-cycloalkyl-N-lower alkyl-amino, in which cycloalkyl has from three to eight, preferably from five to seven, ring carbon atoms, e.g. N-cyclopentyl-N-methyl-amino, N-cyclohexyl-N-ethyl-amino and the like, N-lower alkyl-N-phenyl-lower alkyl-amino, e.g. N-benzyl-N-methyl-amino, N-ethyl-N-(1-phenylethyl)-amino, N-methyl-N-(phenylethyl)-amino and the like, or any other N,N-disubstituted amino group, such as, for example, N-lower hydroxy-alkyl-N-lower alkyl-amino, in which hydroxyl is separated from the nitrogen by at least two carbon atoms, e.g. N-ethyl-N-(2-hydroxyethyl)-amino and the like, or N,N-di-lower hydroxy-alkyl-amino, e.g. N,N-di-(2-hydroxyethyl)-amino and the like.

The N,N-disubstituted amino portion of the N,N-disubstituted amino-lower alkyl group may also be N,N-alkylene-imino, in which alkylene has from three to eight, preferably from four to six, carbon atoms, e.g. 1-pyrrolidino, 1-piperidino, 2-methyl-1-piperidino, 1-N,N-(1,6-hexylene)-imino, 1-N,N-(1,7-heptylene)-imino and the like, N,N-oxa-alkylene-imino, in which alkylene has preferably four carbon atoms, e.g. 4-morpholino and the like, N,N-thia-alkylene-imino, in which alkylene has preferably four carbon atoms, e.g. 4-thia-morpholino and the like, or N,N-aza-alkylene-imino, in which alkylene has from four to six carbon atoms, and in which the azanitrogen may be substituted, for example, by lower alkyl, e.g. methyl, ethyl, isopropyl and the like, hydroxy-lower alkyl, in which hydroxyl is separated from the nitrogen by at least two carbon atoms, e.g. 2-hydroxyethyl and the like, lower alkanoyloxy-lower alkyl, in which lower alkanoyloxy is separated from the nitrogen by at least two carbon atoms, e.g. 2-acetoxyethyl and the like, phenyl-lower alkyl, e.g. benzyl, diphenylmethyl, 2-phenylethyl and the like, or any other suitable substituent, and which may be represented by piperazino, 4-methyl-1-piperazino, 4-ethyl-piperazino, 4-(2-hydroxyethyl)-1-piperazino, 4-(2-

acetyloxyethyl)-1-piperazino, 4-benzyl-1-piperazino, 1-N,N-(3-aza-3-methyl-1,6-hexylene)-imino, 1-N,N-(4-aza-4-methyl-1,7-heptylene)-imino and the like.

As mentioned above, the lower alkyl portion of the N,N-disubstituted amino-lower alkyl substituent of the 5-position of the thiazole nucleus separates the N,N-disubstituted amino group from the latter by at least two carbon atoms; it is represented by lower alkylene having from two to seven, preferably from two to three carbon atoms and separating N,N-disubstituted amino from the 5-position by at least two, preferably by from two to three, carbon atoms. It stands for 1,2-ethylene, 1-methyl-1,2-ethylene, 2-methyl-1,2-ethylene or 1,3-propylene as well as, 1-methyl-1,3-propylene, 2-methyl-1,3-propylene, 1,4-butylene, 1-methyl-1,4-butylene, 1,5-pentylene 1,6-hexylene, 1,7-heptylene and the like.

The N,N-disubstituted amino-lower alkyl substituent attached to the 5-position may also be represented by a group, in which the N,N-disubstituted amino portion forms part of a saturated ring system, which is connected directly or through a lower alkylene group with the 5-position of the thiazole nucleus, and in which the N,N-disubstituted amino group is separated from the latter by at least two carbon atoms. Such groups are, for example, 1-methyl-3-pyrrolidinyl, 1-methyl-3-pyrrolidinylmethyl, 1-ethyl-3-piperidyl, 1-methyl-4-piperidyl, 1-methyl-3-piperidyl-methyl and the like.

Salts of the compounds of this invention are acid addition salts, such as pharmaceutically acceptable acid addition salts with inorganic acids, e.g. hydrochloric, hydrobromic, nitric, sulfuric, phosphoric acids and the like, or with organic carboxylic acids, e.g. acetic, propionic, glycolic, malonic, succinic, maleic, hydroxymaleic, fumaric, malic, tartaric, citric, glucuronic, benzoic, mandelic, salicylic, 4-aminosalicylic, 2-phenoxybenzoic, 2-acetoxybenzoic, pamoic, nicotinic, isonicotinic acid and the like, or organic sulfonic acids, e.g. methane sulfonic, ethane sulfonic, 2-hydroxy-ethane sulfonic, ethane 1,2-disulfonic, p-toluene sulfonic, naphthalene 2-sulfonic acid and the like. Other acid addition salts are used as intermediates, for example, in the preparation of other acid salts or in the purification of the free compounds, as well as for characterization and identification purposes. Salts for the latter are, for example, those with certain inorganic acids, e.g. perchloric acid and the like, with acidic organic nitro compounds, e.g. picric, picrolonic, flavianic acid and the like, or with metal complex acids, e.g. phosphotungstic, phosphomolybdic, chloroplatinic, Reinecke acid and the like. Mono or poly-salts are formed depending on the number of salt forming groups present in the molecule.

Quaternary ammonium derivatives of the compounds of this invention are those with reactive esters from alcohols and strong inorganic and organic acids, particularly the lower alkyl or phenyl-lower alkyl quaternary ammonium halides, sulfates or sulfonates, such as those with lower alkyl halides, e.g. methyl, ethyl, n-propyl, isopropyl or n-butyl chloride, bromide or iodide and the like, phenyl-lower alkyl halides, e.g., benzyl, 1-phenylethyl or 2-phenylethyl chloride or bromide and the like, di-lower alkyl sulfates, e.g. dimethyl sulfate, diethyl sulfate and the like, or lower alkyl sulfonates, e.g. methyl or ethyl methane sulfonate, ethane sulfonate or p-toluene sulfonate and the like. Also included as the quaternary ammonium compounds are the quaternary ammonium hydroxides and other quaternary ammonium salts, in which the anion is derived from an acid other than hydrohalic, sulfuric or sulfonic acid.

The compounds of this invention may be represented by the formula

in which Ar is a carbocyclic aryl radical, Am₁ stands for N-unsubstituted amino, N-monosubstituted amino or N,N-disubstituted amino, Am₂ is N,N-disubstituted amino, the letter n stands for an integer from two to seven, and the group $-(\text{C}_n\text{H}_{2n})-$ separates the N,N-disubstituted amino group Am₂ from the 5-piston of the thiazole ring by at least two carbon atoms, or salts thereof, as well as quaternary ammonium compounds thereof.

The compounds of the present invention antagonize the pressure effects of norepinephrine, thus causing a lowering of the blood pressure. It has been found that this effect is due to a blockade of the nervous transmission along the post-ganglionic sympathetic nerve system, as the compounds do not act centrally, nor along the preganglionic sympathetic nerve pathway or at the ganglia. An additional advantage of the compounds of this invention is the quick onset of the pharmacological action. They are, therefore, useful as anti-hypertensive agents in the treatment of mild hypertension.

Particularly useful are the compounds of the formula

in which Ph stands for phenyl, (lower alkyl)-phenyl, (trifluoromethyl)-phenyl, (lower alkoxy)-phenyl, (N,N-di-lower alkyl-amino)-phenyl or, more especially, halo-
geno-phenyl, Am₂' is N,N-di-lower alkyl-amino, the letter n' stands for one of the integers 2 and 3, especially 2, and the group $-(\text{C}_n'\text{H}_{2n'})-$ separates the group Am₂' from the 5-position of the thiazole ring from two to three, particularly by two, carbon atoms, or acid addition salts, such as pharmaceutically acceptable acid addition salts, thereof.

The compounds of this invention are useful in the form of compositions for enteral or parenteral use, which comprise essentially a pharmacologically effective amount of one of the above compounds in admixture with a solid or liquid carrier. For making up the preparations there are employed known carrier substances, such as water, gelatine, sugars, e.g. lactose, glucose, sucrose, and the like, starches, e.g. wheat starch, corn starch and the like, stearic acid or salts thereof, e.g. magnesium stearate, calcium stearate and the like, stearyl alcohol, talc, vegetable oils, ethanol, benzyl alcohols, gums, propylene glycol, poly-alkylene glycols or any other known carrier material used for the manufacture of such preparations. The latter are in the solid form, e.g. as capsules, tablets, dragees, suppositories and the like, or in liquid form, e.g. as solutions, suspensions, emulsions and the like. If desired, they may contain auxiliary substances, such as preserving, stabilizing, wetting, emulsifying agents and the like, salts for varying the osmotic pressure, buffers, etc. They may also contain, in combination, other useful substances.

The compounds of this invention may be prepared according to methods known per se. For example, they are formed by reacting an α -reactive esterified hydroxy-N,N-disubstituted amino-lower alkyl carbocyclic aryl ketone, in which the N,N-disubstituted amino group is separated from the carbon atom carrying the reactive esterified hydroxyl group by at least two carbon atoms, particularly a compound of the formula

in which Ar, Am₂, the letter n and the group of the formula $-(\text{C}_n\text{H}_{2n})-$ have the previously given meaning, and X₁ stands for a reactive esterified hydroxyl group, or a salt thereof, with a thiourea, particularly a compound having one of the tautomeric formulae:

in which Am₁ has the previously given meaning, and, if

desired, converting a resulting salt into the free compound or into another salt, and/or, if desired, converting a resulting compound into a salt thereof, and/or, if desired, converting a resulting compound into a quaternary ammonium compound thereof, and/or, if desired, converting a quaternary ammonium compound into another quaternary ammonium compound thereof.

In the above starting materials, the reactive esterified hydroxyl group, such as the group X_1 of the compounds of the above formula, is primarily halogeno, e.g. chloro, bromo, iodo and the like; it may also be an organic sulfonyloxy group, e.g. methane sulfonyloxy, ethane sulfonyloxy, p-toluene sulfonyloxy and the like.

The reaction is carried out by mixing the two ingredients, preferably in the presence of a solvent, e.g. methanol, ethanol and the like, or solvent mixture, if necessary, while cooling or at an elevated temperature, in a closed vessel and/or in the atmosphere of an inert gas, e.g. nitrogen.

The starting materials used in the above procedure are prepared, for example, by esterifying the hydroxyl group in an α -hydroxy-N,N-disubstituted amino-lower alkyl carbocyclic aryl ketone, for example, with an organic sulfonic acid halide, or, more especially, by introducing a halogeno (representing a hydroxyl group esterified with a hydrohalic acid) into the α -position of an N,N-disubstituted amino-lower alkyl carbocyclic aryl ketone, in which the N,N-disubstituted amino group is separated from the carbonyl portion by at least three carbon atoms. The latter procedure may be carried out, for example, by reacting the ketone or a salt thereof with halogen, particularly bromine, as well as chlorine and the like, in the presence of a suitable solvent, e.g. acetic acid and the like, which may contain a hydrogen halide, e.g. hydrogen bromide, hydrogen chloride and the like, to facilitate halogenation.

A modification of the above procedure comprises reacting an N,N-disubstituted amino-lower alkyl carbocyclic aryl ketone, in which N,N-disubstituted amino is separated from the carbonyl group by at least three carbon atoms, particularly a compound of the formula

in which Ar, Am₂, the letter n and the group of the formula $-(\text{C}_n\text{H}_{2n})-$ have the previously given meaning, or a salt thereof with a thiourea, particularly a compound having one of the tautomeric formulae

in which Am₁ has the previously given meaning, in the presence of a suitable ring closing reagent, and, if desired, carrying out the optional steps.

Ring-closing reagents useful in the above reaction are reagents containing halogen and having oxidative properties, e.g. iodine, sulfuryl chloride, thionyl chloride, chlorosulfonic acid, sulfur monochloride and the like, as well as reagents without halogen, e.g., sulfur trioxide, sulfuric acid and the like; these reagents may cause the oxidation of the thiourea compound to a formamidine disulfide of the formula

in which Am₁ has the previously given meaning, and which in the above ring closure may replace the thiourea compound and react with the starting material. The reaction is carried out according to known methods.

The starting material (which is also used for the manufacture of the starting material in the previously mentioned process modification) is prepared by treating a reactive esterified hydroxyl-lower alkyl carbocyclic aryl

ketone, particularly a halogeno-lower alkyl carbocyclic aryl ketone, in which the reactive esterified hydroxyl group, particularly the halogeno atom, is separated from the carbonyl group by at least three carbon atoms, with a secondary amine, particularly an amine of the formula Am₂-H, in which Am₂ has the previously given meaning.

The compounds of this invention may also be prepared by reacting an α -thiocyanato-N,N-disubstituted amino-lower alkyl carbocyclic aryl ketone, in which the N,N-disubstituted amino group is separated from the carbon atom carrying the thiocyanato group by at least two carbon atoms, particularly a compound of the formula

in which Ar, Am₂, the letter n and the group of the formula $-(\text{C}_n\text{H}_{2n})-$ have the previously given meaning, or a salt thereof with ammonia, a primary amine or a secondary amine, particularly a compound of the formula Am₁-H, in which Am₁ has the previously given meaning, and, if desired, carrying out the optional steps.

The reaction is carried out according to known methods; the starting material may be obtained from the previously described α -reactive esterified hydroxyl-lower alkyl carbocyclic aryl ketone, particularly an α -halogeno-N,N-disubstituted amino-lower alkyl carbocyclic aryl ketone, in which N,N-disubstituted amino is separated from the carbon atom carrying halogeno by at least two carbon atoms, by treatment with an alkali metal thiocyanate, e.g. sodium thiocyanate and the like, or an alkaline earth metal thiocyanate, e.g. barium thiocyanate and the like.

The compounds of this invention may also be prepared by reacting a 2-amino-4-carbocyclic aryl-5-reactive esterified hydroxyl-lower alkyl-thiazole, in which the reactive esterified hydroxyl group is separated from the 5-position of the thiazole nucleus by at least two carbon atoms, particularly a compound of the formula

in which Am₁, Ar, the letter n and the group of the formula $-(\text{C}_n\text{H}_{2n})-$ have the previously given meaning, and X₂ stands for a reactive esterified hydroxyl group, or a salt of such compound, with an N,N-disubstituted amine, particularly an amine of the formula Am₂-H, in which Am₂ has the previously given meaning, and, if desired, carrying out the optional steps.

The above reaction is carried out according to known methods, preferably in the presence of an inert solvent and, if necessary, of a base to neutralize generated acid (which may also be achieved by using an excess of the amine), while cooling or at an elevated temperature, in a closed vessel and/or in the atmosphere of an inert gas, e.g. nitrogen.

The starting material may be prepared according to known methods, for example, the above given procedure for the formation of the thiazole nucleus using the appropriate starting materials, and, if necessary, a hydroxyl group in a resulting compound may be converted into the desired reactive esterified hydroxyl group.

The compounds of this invention may also be prepared by reacting a 2-halogeno-4-carbocyclic aryl-5-N,N-disubstituted amino-lower alkyl-thiazole, in which N,N-disubstituted amino is separated from the 5-position of the thiazole nucleus by at least two carbon atoms, particularly a compound of the formula

in which Ar, Am₂, the letter n and the group of the formula $-(\text{C}_n\text{H}_{2n})-$

have the previously given meaning, and Hal stands for halogeno, or a salt thereof, with ammonia, a primary amine or a secondary amine, particularly a compound of the formula Am_1-H , in which Am_1 has the previously given meaning, and, if desired, carrying out the optional steps.

The above reaction is carried out according to known methods, if necessary, in the presence of a suitable solvent and/or a base to neutralize the generated acid (which may also be accomplished by using an excess of ammonia or the amine,) in a closed vessel, at an elevated temperature, and/or under an atmosphere or inert gas, e.g. nitrogen.

The starting material may be prepared, for example, by reacting one of the previously described α -thiocyanato- N,N -disubstituted amino-lower alkyl carbocyclic aryl ketones with a hydrogen halide, e.g. hydrogen chloride and the like.

A resulting salt may be converted into the free compound according to known methods, for example by treatment with a basic reagent, such as a metal hydroxide, for example, an alkali metal hydroxide or an alkaline earth metal hydroxide, e.g. sodium hydroxide, potassium hydroxide, calcium hydroxide and the like, a metal carbonate, such as an alkali metal carbonate, or an alkaline earth metal carbonate, e.g. sodium, potassium or calcium carbonate or hydrogen carbonate and the like, ammonia, a hydroxyl ion exchange preparation and the like.

A resulting salt is converted into another salt according to known methods, for example, by treatment with a suitable anion exchange preparation. Furthermore, an addition salt with an inorganic acid may be converted into another acid addition salt, for example, by treating it with a suitable metal salt, e.g. silver, sodium and the like, salt of an acid in the presence of a solvent or solvent mixture, in which a resulting inorganic compound is insoluble and is thus removed from the reaction medium.

A free compound is converted into a salt thereof according to known methods, for example, by reacting the free base or a solution thereof with one of the previously mentioned acids or a solution thereof, or with a suitable anion exchange preparation, and isolating the desired salt, which may be in the form of a hydrate or may contain solvent of crystallization.

The quaternary ammonium derivatives of the compounds of this invention are obtained according to known methods, for example, by reacting the free compound with the reactive ester of an alcohol and a strong inorganic or organic acid, such as a lower-alkyl halide, a phenyl-lower alkyl halide, a lower alkyl sulfonate, a di-lower alkyl sulfate and the like, if necessary, in the presence of a solvent or solvent mixture, at an elevated temperature, in a closed vessel, and/or in the atmosphere of an inert gas, e.g. nitrogen. The quaternary ammonium compounds may be isolated as the hydrates.

Quaternary ammonium compounds can be converted into other quaternary ammonium derivatives, such as the quaternary ammonium hydroxides, for example, by reacting a quaternary ammonium halide with silver oxide, or a quaternary ammonium sulfate with barium hydroxide, by treating a quaternary ammonium salt with a hydroxyl ion exchange preparation, by electrodialysis or any other suitable method. A resulting quaternary ammonium hydroxide compound is converted into a quaternary ammonium salt, for example by reaction with an acid, a mono-lower alkyl sulfate, e.g. methyl sulfate, ethyl sulfate and the like, a suitable anion exchange preparation and the like. A quaternary ammonium compound may also be converted directly into another quaternary ammonium salt without the formation of the quaternary ammonium hydroxide; for example, a quaternary ammonium iodide may be reacted with freshly prepared silver chloride or hydrogen chloride in anhydrous methanol to form the quaternary ammonium chloride, or upon treatment with a suitable anion exchange preparation a

quaternary ammonium compound may be converted into another quaternary ammonium salt.

The invention also comprises any modification of the process wherein a compound obtainable as an intermediate at any stage of the process is used as starting material and the remaining step(s) of the process is (are) carried out, as well as any new intermediates.

In the process of this invention such starting materials are preferably used which lead to final products 10 mentioned as preferred embodiments of the invention.

The following examples are intended to illustrate the invention and are not to be construed as being limitations thereon. Temperatures are given in degrees centigrade.

Example 1

To a solution of 0.37 g. of thiourea in 7.5 ml. of ethanol is added 2.0 g. of α -bromo-p-chloro- γ -(N,N -diethylamino)-butyrophenone hydrobromide, and the reaction mixture is warmed on the steam bath for ten minutes. A 20 crystalline precipitate is formed on cooling and is filtered off to give the 2-amino-4-(4-chlorophenyl)-5-(2- N,N -diethylaminoethyl)-thiazole dihydrobromide of the formula

30 which is purified by recrystallization from a mixture of ethanol and water, M.P. 227-228°.

The starting material may be prepared as follows: A mixture of 100 g. of p,γ -dichloro-butyrophenone and 41.5 g. of N,N -dimethylamine in 320 ml. of ethanol is heated in an autoclave for 10 hours. After cooling, the ethanol is evaporated, the residue is dissolved in water, and the solution is made basic with aqueous ammonia. The organic material is extracted with diethyl ether, the organic solution is shaken with 15 percent aqueous hydrochloric acid, and the acidic extract is made basic with aqueous ammonia. The p -chloro- γ - N,N -diethylamino-butyrophenone is extracted with diethyl ether, the organic solution is dried over sodium sulfate and evaporated, and the residue is distilled, B.P. 120-122°/0.8 mm. The hydrochloride, M.P. 169-171°, is prepared by treating the free base with hydrogen chloride and purified by recrystallization from a mixture of ethanol and diethyl ether.

To a solution of 5.0 g. of p -chloro- γ - N,N -dimethylamino-butyrophenone hydrochloride in 15 ml. of glacial 50 acetic acid is added 19 ml. of a 1 molar solution of bromine in glacial acetic acid as follows: about 2 ml. of the halogenating reagent is added and the solution is warmed to about 50° for a few minutes until the bromine decolorizes. The solution is then cooled to room temperature,

55 and the remainder of the reagent is then added dropwise while stirring over a period of about thirty minutes at such a rate that an excess of bromine is never present in the reaction mixture for more than a few seconds. After completion of the reaction, diethyl ether is added to turbidity, the reaction flask is allowed to stand overnight while cooling and the crystalline material is filtered off. The α -bromo-p-chloro- γ - N,N -dimethylamino-butyrophenone hydrobromide is recrystallized from ethanol and melts at 135°.

60 The following compounds are prepared according to the above or any of the previously described procedures by selecting the appropriate starting materials:

65 2-amino - 4 - (4-chloro-phenyl)-5-[2-(1-pyrrolidino)-ethyl]-thiazole dihydrobromide, M.P. 262-264°, by reacting an ethanol solution of thiourea with α -bromo-p-chloro- γ -(1-pyrrolidino)-butyrophenone hydrobromide, M.P. 134-135° (prepared by reacting p,γ -dichloro-butyrophenone with pyrrolidine and brominating the p -chloro- γ -(1-pyrrolidino)-butyrophenone hydrochloride, M.P. 168-170°, the free base of which melts at 58-60°);

2 - amino - 5 - (2-N,N-dimethylaminoethyl)-4-(4-methoxy-phenyl)-thiazole dihydrobromide, M.P. 255-258°, by reacting an ethanol solution of thiourea with α -bromo- γ -(N,N-dimethylamino)-p-methoxy - butyrophenone hydrobromide M.P. 153-165° (prepared by reacting γ -chloro-p-methoxy-butyrophenone with N,N-dimethylamine and brominating the γ -(N,N-dimethylamino)-p-methoxy-butyrophenone hydrochloride, M.P. 150°, the free base of which boils at 150-156°/0.75 mm.);

2 - amino - 4 - (4-bromo-phenyl)-5-(2-N,N-dimethylaminoethyl)-thiazole dihydrobromide, M.P. 248-250°, by reacting thiourea with p, α -dibromo- γ -(N,N-dimethylamino)-butyrophenone hydrobromide, M.P. 96-98° (prepared by reacting p-bromo- γ -chloro-butyrophenone with N,N-dimethylamine and brominating the p-bromo- γ -(N,N-dimethylamino)-butyrophenone hydrochloride, M.P. 193-195°, the free base of which boils at 119-120°/0.19 mm.);

2-amino - 5 - (2-N,N-dimethylaminoethyl)-4-(N,N-dimethylamino-phenyl)-thiazole dihydrobromide, M.P. 196-200°, by reacting thiourea with α -bromo-p, γ -bis-(N,N-dimethylamino)-butyrophenone hydrobromide, M.P. 200-202° (prepared by reacting γ -chloro-p-(N,N-dimethylamino)-butyrophenone with N,N-dimethylamine and brominating the p, γ -bis-(N,N-dimethylamino)-butyrophenone hydrochloride);

2-amino - 4 - phenyl-5-[2-(1-pyrrolidino)-ethyl]-thiazole dihydrobromide, M.P. 267-269°, by reacting thiourea with α -bromo- γ -(1-pyrrolidino)-butyrophenone hydrobromide, M.P. 96-98° (prepared by reacting γ -chloro-butyrophenone with pyrrolidine and brominating the γ -(1-pyrrolidino)-butyrophenone hydrochloride, M.P. 162-163°), as well as the following compounds by selecting the appropriate starting materials and reagents;

α -Halogeno-N,N-disubstituted amino-lower alkyl carbocyclic aryl ketone	Thiourea	2-amino-4-carbocyclic aryl-5-N,N-disubstituted amino-lower alkylthiazole
α -Bromo-p-chloro- γ N,N-diethylaminobutyrophenone	Thiourea	2-amino-4-(4-chlorophenyl)-5-(2-N,N-diethylaminoethyl)-thiazole.
α -Bromo- γ -N,N-diethylamino-p-isopropyl-butyrophenone	do	2-amino-5-(2-N,N-diethylaminoethyl)-4-(4-isopropyl-phenyl)thiazole.
α -Bromo- γ -N,N-diethylamino-p-trifluoromethyl-butyrophenone	do	2-amino-5-(2-N,N-diethylaminoethyl)-4-(4-trifluoromethyl-phenyl)-thiazole.
α , β -dibromo- γ -(1-piperidino)-butyrophenone	do	2-amino-4-(4-bromo-phenyl)-5-[2-(1-piperidino)-ethyl]-thiazole.
α -Bromo- γ -N,N-dimethylamino-p-tertiary butyl-butyrophenone	do	2-amino-5-(2-N,N-di-methylamino ethyl)-4-(4-tertiary butyl-phenyl)-thiazole.
α -Bromo- γ -N,N-dimethylamino-p-fluoro-butyrophenone	do	2-amino-5-(2-N,N-di-methylaminoethyl)-4-(4-fluoro-phenyl)-thiazole.
α -Bromo-m,p-dichloro- γ -N,N-di-n-propylamino-butyrophenone	do	2-amino-4-(3,4-dichlorophenyl)-5-(2-N,N-di-n-propyl-amino-ethyl)-thiazole.
α -Bromo-o,p-dimethyl- γ -(1-N,N-(1,6-hexylene)-imino)-thiazole	do	2-amino-4-(2,4-dimethylphenyl)-5-[2-(1-N,N-(1,6-hexylene)-imino-ethyl)-thiazole.
α -Bromo-p-chloro- γ -(4-morpholino)-thiazole	do	2-amino-4-(4-chlorophenyl)-5-[2-(4-morpholino)-ethyl] thiazole.
α -Bromo-o-ethoxy- γ -(4-methyl-1-piperazinol)-butyrophenone	do	2-amino-4-(2-ethoxy-phenyl)-5-[2-(4-methyl-1-piperazino)-ethyl]-thiazole.
α -Bromo- γ ,p-di-(N,N-diethylamino)-butyrophenone	do	2-amino-5-(2-N,N-diethylaminoethyl)-4-(4-N,N-diethylamino-phenyl)-thiazole.
α -Bromo- γ -N,N-di-ethylamino-p-methylmercapto-butyrophenone	do	2-amino-5-(2-N,N-diethylaminoethyl)-4-(4-methyl-mercapto-phenyl)-thiazole.

NOTE.—The above compounds are also obtained in the form of acid addition salts thereof.

Example 2

To a solution of 2.0 g. of 2-amino-4-(4-chloro-phenyl)-5-2-N,N-dimethylaminoethyl)-thiazole dihydrobromide is added ammonium hydroxide; the crystalline 2-amino-4-(4-chloro-phenyl)-5-(2-N,N-dimethylaminoethyl) - thiazole is filtered off and recrystallized from aqueous ethanol, M.P. 165-167°. Upon treating the free base with 5 N solution of hydrogen chloride, it is converted into the hygroscopic 2-amino-4-(4-chloro-phenyl) - 5 - (2-N,N-di-methylaminoethyl)-thiazole dihydrochloride, which melts at 127-130° after recrystallization from ethanol.

Example 3

To a solution of 0.55 g. of thiourea in 5 ml. of ethanol is added 2.5 g. of α -bromo- γ -(N,N-dimethylamino)-butyrophenone hydrobromide. After refluxing for five minutes, the reaction mixture is cooled and diluted with diethyl ether. The resulting precipitate is filtered off, and dissolved in water; the aqueous solution is treated with

70

10

an aqueous sodium hydroxide solution, and the crystalline 2-amino-5-(2-N,N-dimethylaminoethyl) - 4 - phenylthiazole of the formula

5

10 is recrystallized from ethanol, M.P. 150-155°.

The starting material is prepared as described in Example 1; the α -bromo- γ -(N,N-dimethylamino)-butyrophenone hydrobromide, M.P. 176-178° is obtained by reacting γ -chloro-butyrophenone with N,N-dimethylamine and brominating the resulting γ -(N,N-dimethylamino)-butyrophenone hydrochloride, the free base of which boils at 103-106°/0.8 mm.

Example 4

The 2 - amino-4-(4-chloro-phenyl)-5-(3-N,N-dimethylaminopropyl)-thiazole dihydrobromide of the formula

20

is prepared by reacting 0.45 g. of α -bromo-p-chloro- δ -(N,N - dimethylamino) - valerophenone hydrobromide (M.P. 138°, prepared by heating p, δ -dichloro-valerophenone with N,N-dimethylamine in ethanol in a sealed tube and brominating the p-chloro- δ -(N,N-dimethylamino)-valerophenone hydrochloride, M.P. 121-124°) with an equivalent amount of thiourea according to the

95

procedure described in Example 1; the desired product melts at 274-276° after recrystallization from ethanol.

Example 5

An equivalent amount of thiourea in ethanol is treated with 1.0 g. of 1-bromo-5-(N,N-dimethylamino)-pentyl 4-chloro-phenyl ketone hydrobromide according to the procedure described in Example 1; the 2-amino-4-(4-chloro-phenyl)-5-(4-N,N-dimethylaminobutyl) - thiazole dihydrobromide of the formula

70

75

80

85

90

95

100

is recrystallized from a mixture of ethanol and ethyl acetate, M.P. 225°.

The starting material is prepared as described in Example 1; the 4-chloro-phenyl 5-(N,N-dimethylamino)-

pentyl ketone hydrochloride, M.P. 178-180°, is brominated to yield the 1-bromo-5-(N,N-dimethylamino)-pentyl 4-chloro-phenyl ketone hydrobromide, M.P. 135-138°.

Example 6

A mixture of 1.6 g. of α -bromo- γ -(N,N-dimethylamino)-p-methoxy-butyrophenone hydrobromide and 0.65 g. of N-phenylthiourea in 10 ml. of ethanol is reacted according to the procedure described in Example 1 to yield the 4-(4-methoxy-phenyl)-5-(2-N,N-dimethylaminoethyl)-2-N-phenylamino-thiazole dihydrobromide of the formula

which melts at 121-125° after recrystallization from a mixture of ethanol and diethyl ether.

Other compounds, which may be prepared according to the above procedure by selecting the appropriate starting materials are, for example,

α -Halogeno-N,N-disubstituted amino-lower alkyl carbocyclic aryl ketone	N-substituted thiourea	2-(N-substituted amino)-4-carbocyclic aryl-5-N,N-disubstituted amino-lower alkyl-thiazole
α -Bromo-p-chloro- γ -N,N-diethylamino-butyrophenone	N-methylthiourea	4-(4-chloro-phenyl)-5-(2-N,N-diethylaminoethyl)-2-N-methylaminothiazole.
δ -Bromo- γ -N,N-dimethylamino- α -methyl-butyrophenone	N,N-dimethylthiourea	2-N,N-dimethylamino-5-(2-N,N-dimethylaminoethyl)-4-(2-methyl-phenyl)-thiazole.
α , β -Dibromo- γ -N,N-dimethylamino-valerophenone	N-ethylthiourea	4-(3-bromo-phenyl)-2-N-ethylamino-5-(2-N,N-dimethylamino-2-methylethyl)-thiazole.
α -Bromo-p-methylmercapto- γ -(1-piperidino)-butyrophenone	N-cyclohexylthiourea	2-N-cyclohexylamino-4-(4-methylmercaptophenyl)-5-[2-(1-piperidino)-ethyl]-thiazole.
α -Bromo-p-chloro- δ -N,N-dimethylamino-valerophenone	N-benzylthiourea	2-N-benzylamino-4-(4-chloro-phenyl)-5-(3-N,N-dimethylaminopropyl)-thiazole.
α -Bromo- γ -N,N-diethylamino-p-nitrobutyrophenone	N-(4-chlorophenyl)-thiourea	2-N-(4-chlorophenyl)-amino-5-(2-N,N-diethylaminoethyl)-4-(4-nitrophenyl)-thiazole.

NOTE.—The above compounds may also be obtained in the form of acid addition salts thereof.

Example 7

A mixture of 10.0 g. of 2-amino-5-(2-chloroethyl)-4-(4-chloro-phenyl)-thiazole hydrobromide and 50 ml. of a 10 percent solution of N,N-dimethylamine in ethanol is heated at 80° in a rocking brom tube for twenty-four hours. The solution is then evaporated to dryness, the residue is stirred with 50 ml. of aqueous ammonia, and the mixture is chilled. The solid material is filtered off and dissolved in a small amount of ethanol; gaseous hydrogen bromide is passed through the solution, and the desired 2-amino-4-(4-chloro-phenyl)-5-(2-N,N-dimethylaminoethyl)-thiazole dihydrobromide is filtered off, M.P. 227-228°.

The starting material used in the above procedure is prepared as follows: A mixture of 3.0 g. of α -bromo-p, γ -dichlorobutyrophenone (M.P. 71-73°, prepared by brominating p, γ -dichlorobutyrophenone with bromine in the presence of 1 ml. of 48 percent hydrogen bromide in acetic acid) and 1.0 g. of thiourea in 10 ml. of ethanol is refluxed for ten minutes. The crystalline 2-amino-5-(2-chloroethyl)-4-(4-chloro-phenyl)-thiazole hydrochloride is filtered off and recrystallized from a mixture of ethanol and n-propanol and twice from water.

What is claimed is:

1. A member selected from the group consisting of a compound of the formula

in which Ar is a member selected from the group consisting of phenyl, (lower alkyl)-phenyl, (trifluoromethyl)-phenyl, (lower alkoxy)-phenyl, (N,N-di-lower alkyl-amino)-phenyl, (halogeno)-phenyl and (lower alkyl-mercapto)-phenyl, Am₁ is a member selected from the group consisting of amino, N-lower alkyl-amino, N,N-di-lower alkyl-amino, N-cycloalkyl-amino, in which cycloalkyl has from three to eight carbon atoms, N-phenyl-amino, and N-phenyl-lower alkyl-amino, Am₂ is a member selected from the group consisting of N,N-di-lower alkyl-amino, N,N-alkylene-imino, in which alkylene has from three to seven, and the group $-(C_nH_{2n})-$ separates the group Am₂ from the 5-position of the thiazole ring by at least

15 20 25 30 35 40 45 50 55 60

two carbon atoms, and a pharmaceutically acceptable acid addition salt thereof.

- 40 2. 2-amino-4-(4-chloro-phenyl)-5-(2-N,N-dimethylaminoethyl)-thiazole.
3. Pharmaceutically acceptable acid addition salts of 2-amino-4-(4-chloro-phenyl)-5-(2-N,N-dimethylaminoethyl)-thiazole.
- 45 4. 2-amino-4-(4-chloro-phenyl)-5-(2-N,N-dimethylaminoethyl)-thiazole dihydrochloride.
5. 2-amino-4-(4-chloro-phenyl)-5-(2-N,N-dimethylaminoethyl)-thiazole dihydrobromide.
- 50 6. 2-amino-5-(2-N,N-dimethylaminoethyl)-4-phenylthiazole.
7. 2-amino-5-(2-N,N-dimethylaminoethyl)-4-(4-methoxyphenyl)-thiazole.
- 55 8. 2-amino-4-(4-bromo-phenyl)-5-(2-N,N-dimethylaminoethyl)-thiazole.
9. 2-amino-4-(4-N,N-dimethylamino-phenyl)-5-(2-N,N-dimethylaminoethyl)-thiazole.
10. 2-amino-4-(4-chloro-phenyl)-5-(4-N,N-dimethylaminobutyl)-thiazole.
11. 5-(2-N,N-dimethylaminoethyl)-4-(4-methoxy-phenyl)-2-N-phenyl-amino-thiazole.

UNITED STATES PATENT OFFICE
CERTIFICATE OF CORRECTION

Patent No. 3,210,368

October 5, 1965

Charles Ferdinand Huebner

It is hereby certified that error appears in the above numbered patent requiring correction and that the said Letters Patent should read as corrected below.

Column 12, line 52, for "-4,(4-meth-)" read -- -4-(4-meth- --; lines 54 and 58, for ")thiazole", each occurrence, read --)-thiazole --.

Signed and sealed this 9th day of August 1966.
